UNITED STATES PATENT OFFICE.

ARTHUR W. POPE, JR., OF WAUKESHA, WISCONSIN, ASSIGNOR TO WAUKESHA MOTOR COMPANY, OF WAUKESHA, WISCONSIN, A CORPORATION OF WISCONSIN.

HEATER.

Application filed April 8, 1925. Serial No. 21,490.

This invention relates to heaters, particularly to a heater structure or stove adapted to be attached to an explosive engine in association with the exhaust manifold to automatically control the temperature of the air to be delivered to the air intake of the carburetor supplying the engine with explosive mixtures.

In the operation of internal combustion engines, it is desirable to prevent gasoline from depositing itself from the mixture on the intake passage walls in excessive amounts at low manifold velocity, and at high velocity it is desired that the air be comparatively cold in order that the maximum weight of air may pass into the cylinders.

At high manifold velocity there is no trouble from gasoline condensation in the manifold and heating of the intake air is not necessary. However, at low velocity in the intake manifold, that is, when the engine is idling or running light, condensation may result, but by properly heating the air the condensation is in greater part avoided and if there should be any condensation it will be taken up by the hot mixture. The important object of my invention is, therefore, to provide a simple heater or stove in the form of an attachment, which will receive its heat from the engine and which will be automatically controlled by the suction and velocity in the intake manifold to deliver to the carburetor properly tempered air, so that the resulting mixture delivered by the carburetor will permit the most efficient operation of the engine under its different conditions of operation.

Another object is to produce a simple, inexpensive heater structure which is devoid of any movable parts and which will, therefore, require no adjustment or repair.

On the drawings my improved stove and its operation are clearly illustrated;

Figure 1 being a side elevational view partly in section and with parts broken away;

Fig. 2 being a sectional view on plane 2-2 of Fig. 1;

Fig. 3 being a sectional view on plane 3-3 of Fig. 1, and Fig. 4 is a side elevational view of an internal combustion engine showing the heater attached thereto.

The stove body B is of L-shaped cross section, so that it may easily and securely fit over the corner of a support, such as the

exhaust manifold E of the engine, with which the stove is to be associated. The inner side of the stove body is open, so that the walls of the exhaust manifold will form the rear and bottom walls, respectively, of the body. The body has the top wall 10, the vertical rear wall 11 which rests on the exhaust manifold, the front vertical wall 12 spaced away from the manifold front wall, and the lower wall section 13 extending rearwardly from the lower edge of the front wall 12 and engaging against the front wall of the exhaust manifold. At its end the body is closed by the end walls 14 and 15, respectively, which fit the corner of the exhaust manifold. The structure is securely held in place by screws 16 which may thread into the wall of the exhaust manifold so that the structure can be readily removed or applied.

At one end of the structure body, near the lower corner thereof, the inlet opening 17 is provided in the front wall 12 for the entrance of air which is to be heated. At the other end and in front of the body structure is the main air inlet part 18. The body 19 of this part is rectangular and communicates with the interior of the main body B through the passageway 20. In the upper wall of the part 19 is the air inlet opening 21 surrounded by the funnel or nozzle flange 22. Co-axial with the inlet opening 21 the outlet duct 23 extends from the lower wall of the part 19, the space 24 within the part 19 receiving cold air thru the inlet 21 and heated air through passageway 20 the mixture then flowing out through the duct 23. The entire structure involving the body B and part 18 may be a single casting.

The space or chamber 24 is preferably above the level of the exhaust manifold top and the top wall 10 of the body B slopes gradually upwardly to the end of the body B behind the air passage structure 18, so that air entering through the inlet 17 will become heated and flow towards the other end of the body B and from there into the chamber 24, to leave therefrom either upwardly through the inlet 21 or downwardly with cold air through the outlet 23. The air passage part 18, being in front of the body B and the outlet duct 23 being spaced away from the body B, the structure 18 will be practically insulated from the direct heat of the exhaust manifold.

Describing the operation, after the engine has been started the exhaust manifold will soon be heated and the air within the body B of the stove will take up the heat, and if there were no suction effect at the outlet 23, this heated air would tend to flow upwardly out of the air inlet opening 21, the outflowing air being replenished by cool air entering the opening 17 which is lower than the inlet 21. This natural flow will be comparatively slow and the air heating will be maximum. If the engine is idling or running at very light load the condition might be such that the amount of air required by the carbureter will be satisfied by the amount of heated air flowing naturally through the stove, and in such case the heated air, instead of flowing upwardly out of the inlet 21, will flow downwardly through the outlet 23 to the carbureter and there will be little if any cold air flow into the inlet 21. In other words, practically all the air will be supplied from the auxiliary inlet 17 by the natural draft and will be at a maximum temperature. This will be the condition desired, as the heating of the carbureter mixture will be such that condensation will practically be prevented.

As the speed of the engine is increased, the amount of air required will be in excess of the amount which could be produced by the natural draft alone and the increased suction will, therefore, in addition to the heated air, draw in cold air through the inlet 21 to mix with the heated air and to be drawn through the outlet 23 to the carbureter. As before pointed out, the main air structure 18 is insulated from the direct heat of the exhaust manifold, so that the air flowing directly into the inlet 21 will be comparatively cold. The temperature of the air delivered to the carbureter will then depend upon the relative amount of air flowing directly into the part 18 and the heated air flowing through the stove body. As the engine increases to full power the amount of direct cold air will correspondingly increase until the air delivered at the carbureter will be only slightly tempered. On the other hand, when the engine speed is decreased and it is running at very light load or idling, practically only heated air is delivered to the carbureter at a relatively high temperature. When the engine is running at high speed or at full power the velocity of the intake mixture is so great that there will be no chance for any condensation on the manifold walls, and with the air comparatively cold the maximum weight of air will be used in the mixture.

It will be noted that the cross sectional area of the passageway 21 and the passageway 23 is less than that of the intermediate chamber 19 and that the outlet 23 is axially in alignment with the inlet 21, and that the

inlet 21 has the flange or nozzle shaped entrance wall 22. With this arrangement the tendency under heavy suction will be to compact and concentrate the incoming air and to cause it to flow in a solid stream from the inlet to the outlet and across the chamber 24. When there is no suction the heated air flows upwardly and out of the air inlet 21. When the suction becomes effective and during ordinary running of the engine the air coming in at the inlet 21 will have a chance to spread out in the chamber 24 and carry with it heated air in proportion to the degree of suction. However, for heavy power operation of the engine maximum weight of air is required and, therefore, heating of the air should be avoided. The concentration of the air and its flow in a compact stream across the chamber and to the outlet 23, as above explained, will practically shut off the flow of heated air so that the air delivered to the carbureter will not be materially heated.

It will be noted that the stove structure shown is devoid of any movable parts, the entire operation being automatically controlled by the temperature of the stove air, and the suction effect and velocity in the main air supply part 18.

I claim:

1. The combination with an internal combustion engine, of an air heater, said heater being applied to a hot part of the engine structure to receive heat therefrom, said heater having a main air inlet and an auxiliary air inlet below the level of the main air inlet, whereby air entering said auxiliary air inlet will become heated and tend to flow upwardly and out of the main air inlet, an outlet for said heater connected with the air intake of the carbureter for the engine, the suction effect at the heater outlet tending to draw in air through the main air inlet and with it the heated air tending to flow through said main air inlet, the proportion of cold and heated air depending upon the degree of suction effect exerted at the heater outlet.

2. The combination with an internal combustion engine of a heater, said heater being applied to the exhaust manifold of the engine to receive heat therefrom, a main air inlet, and an auxiliary air inlet for said heater relatively located to cause the natural flow of heated air upwardly and out of said main air inlet, an outlet for said heater positioned below the main air inlet and connected with the air intake of the carbureter for the engine, the suction effect at said heater outlet tending to change the direction of flow of the heated air from said heater and drawing it through the outlet together with additional cold air supply through said main air inlet.

3. The combination with an internal com-

- bustion engine of a heater, said heater comprising a body part applied to the heated part of the engine to receive heat therefrom, an air passageway connected with and extending transversely of said body part and displaced from said heated part and having an entrance and an outlet, said body part having an air inlet below the level of said air passageway entrance whereby air entering through said inlet will be heated and will tend to flow through said body part and out of said entrance, said outlet being connected with the air intake of the engine carbureter to be subjected to suction effect 10 when the engine is operated, such suction effect tending to draw the heated air out of the body part through said outlet together with additional cold air supply through said entrance, the proportion of cold air and heated air being dependent upon the degree of suction and the velocity of flow through said air passageway.
4. The combination with an internal combustion engine of a heater, said heater having a main chamber applied to the exhaust manifold of the engine to receive heat therefrom, an intermediate chamber in front of said main chamber and communicating with the upper end of said main chamber, said intermediate chamber having an air entrance at its upper end, and an outlet at its lower end, said main chamber having an air inlet below the level of said air entrance whereby air entering through said inlet will be heated and tend to flow through said chambers and out of said entrance, said outlet being connected with the air intake of the engine carbureter to be subjected to the suction of the engine, the suction effect tending to draw the heated air away from said air entrance and through said outlet, together with cold air through said air entrance, the proportion of cold and heated air depending upon the degree of suction. 35
5. The combination with an internal combustion engine of a heater, said heater having a heating chamber intimately associated with the heated part of the engine to receive heat therefrom, a mixing chamber having a cold air entrance and a mixture outlet, said mixing chamber communicating with said heated chamber, said heated chamber having an air inlet below the level of the mixing chamber air entrance whereby air entering through said inlet will be heated and will flow through said mixing chamber, said mixing chamber outlet being connected with the air intake of the engine carbureter whereby the suction effect will draw cold 50 air into said mixing chamber and the mixture of cold and heated air from said chamber to the carbureter.
6. The combination with an internal combustion engine of a heater, said heater having a heated passageway intimately associated with the heated part of the engine to receive heat therefrom, a cold air passageway displaced from said heated part and communicating with said passageway, said heated passageway having an air inlet below the level of said cold air passageway, air entering through said inlet becoming heated and flowing through said cold air passageway, said passageway being connected with the air intake of the engine carbureter whereby when the engine is operated the suction effect will draw the heated air together with cold air from said cold air passageway to the carbureter. 65 70 75
7. The combination with an internal combustion engine of a heater structure, said structure having a heating passageway intimately associated with the exhaust manifold of the engine to receive heat therefrom, a cold air passageway forming part of said structure and connected with the air intake of the engine carbureter, said heated passageway having an air inlet below the level of said cold air passageway entrance whereby air entering through said inlet will be heated and will flow through the cold air passageway to be available for mixture with the cold air drawn through said passageway to the carbureter when the engine is operating. 80 85 90
8. The combination with an internal combustion engine of a heater structure, said structure having a heating chamber, means for heating the air in said chamber, an intermediate air chamber offset from said heating chamber and away from said heating means, said intermediate chamber having a cold air entrance and having an outlet connected with the air intake of the engine carbureter, said heated chamber having an air inlet below the level of said cold air entrance whereby air entering through the said inlet will be heated and will tend to flow through said intermediate chamber and out of said entrance, suction effect at said outlet tending to divert the heated air to said outlet and to draw cold air through said entrance, and means for causing the air to flow in a concentrated stream through said intermediate chamber from the entrance to the outlet whereby to prevent over mixture of heated air with cold air when the engine is running at full load. 95 100 105 110 115

In witness whereof, I hereunto subscribe my name this 4th day of April, 1925.
